FORCED FEED DRAFT EQUALIZER

William Barends, New York, N. Y.

Application May 14, 1936, Serial No. 79,794

4 Claims. (Cl. 299—129)

This invention relates to a novel accessory, in the nature of an attachment for the discharge nozzle of an electric motor powered blower such as is used as a force-feed draft circulator for 5 coal-fired steam boilers and the like.

Persons familiar with installations of this type are cognizant of the fact that, under ordinary circumstances, the discharge nozzle of the blower casing is operatively connected with the back 10 wall of the skirt portion of the ash pit. That is to say, it is substantially directly beneath the chimney connection, which is also at the back of the structure, and approximately opposite the door-equipped front wall of the ash pit. Under 15 the circumstances the distribution of incoming air is poorly controlled. Theoretically, the air stream is virtually shot in a direct path against the frontal portion of the ash pit. Therefore, the distribution and upward passage of the air 20 lacks requisite uniformity. Consequently, the carbon monoxide gases given off by the burning fuel above the grate tend to hamper proper combustion. It has been discovered, therefore, that by injecting an extra supply of atmospheric air 25 or oxygen above the fire bed, the combustion is more satisfactory and uniform. It is believed, however, that this supplementary supply of air above the fuel bed is not absolutely necessary if the injected air from the floor is properly distributed in the ash pit and allowed to permeate 30 the burning coal properly from beneath.

With these points and objections in mind, I have evolved and produced an air spreader and delivery attachment for the discharge nozzle of 35 the blower which is located within the limits of the ash pit and properly constructed to divert and deflect the air currents through the instrumentality of suitable baffles to bring about the requisite continuous circulation and uniform distribution of air believed sufficient to produce 40 proper combustion in the fire box and to thereby conserve fuel and more effectively control the flame and avoid needless explosions, back-drafts, and possible resulting fires from overheated 45 chimney pipe connections.

In carrying out the principles of the invention I have found it expedient and practicable to utilize a substantially V-shaped baffle unit made up of diverging baffle plates adjustably joined 50 together and cooperable with suitable coupling means applicable to the conventional motor driven blower.

Other features and advantages will become apparent from the following description and the 55 accompanying illustrative drawings.

In the drawings, wherein like numerals are employed to designate like parts throughout the views:

Figure 1 is a view showing the conventional blower in elevation located exteriorly of the ash 5 pit and further showing portions of the boiler in section, as well as the air supply equalizer attachment cooperable with the blower and ash pit;

Figure 2 is a horizontal sectional view showing 10 a top plan version of the equalizer per se, with sufficient of the other structure shown to disclose the relative arrangement of parts;

Figure 3 is a slightly enlarged end elevation 15 of the attachment removed from the ash pit;

Figure 4 is a central longitudinal or horizontal sectional view taken approximately on the plane of the line 4—4 of Figure 3;

Figure 5 is a section which may be described 20 as a cross-section on the line 5—5 of Figure 1;

Figure 6 is a detail perspective view.

Considering now the drawings in detail, and referring to the parts by distinguishing reference numerals, attention is conveniently called to Figure 1, wherein the conventional steam boiler 25 is denoted by the numeral 1. On the interior thereof is the conventional grate, the grate being indicated by the numeral 8 and defining the aforementioned ash pit 10. The front door of the ash pit is conveniently denoted by the numeral 11. The conventional blower is indicated at 12 and embodies the usual discharge nozzle 13. It is with this nozzle and the back wall 9 30 of the ash pit or base that the improved attachment is directly associated. The expression "attachment" is used advisedly, for it is evident that it is possible to manufacture this invention as a permanent adjustable part of the discharge nozzle structure in an air supply blower.

The so-called attachment comprises a coupling 40 collar or sleeve 14 which may be telescopically connected with the nozzle and fastened thereto by a simple removable pin 15. The inner flanged end 16 of the collar rests in contact with the inner surface of the back wall of the ash pit. 45 This provides the requisite adapter fitting for the duplex or two-way air stream equalizer. This equalizer unit is preferably constructed from a single plate or sheet of metal which is bent between its ends to form an attaching and retention member 17 as shown in Figure 4. This is held in place by the aforesaid nail or pin 15. Extending outwardly therefrom in diverging directions are the baffle elements or plates. The inner 50 end portions 18 converge in close proximity to 55

ward the attaching pin. The outer end portions, forming the air divider and shunting blades as at 19, project beyond the flange and spread apart in requisite diverging relation. Interposed 5 therebetween is an arcuate adjusting bolt 20 having nut connections as at 21 with the outer ends of the baffle blades whereby it is possible to adjust the blades toward and from each other. Incidentally, the metal possesses sufficient 10 inherent resiliency to facilitate this adjustment. Along the upper edges of the baffle plates 19 are outwardly bent, properly proportioned, reinforcing and air-distributing flanges 22. Similar narrower and smaller flanges 23 are on the bottom 15 edges of the baffle plates. These upper and lower flanges together with the plate proper coordinate in giving the air the desired tunneling and sweeping action. That is to say, the upper hooked flanges 22 tend to direct the air currents in a 20 more or less horizontal plane and the lower deflector flanges 23 tend to swirl the air currents laterally from the imaginary longitudinal dimension of the structure as a whole. Consequently, these flanged deflector elements spread and direct 25 the air somewhat in the general path or line of the arrows shown in Figure 2. In practice the deflected air jets are swept out toward the opposite sides of the ash pit and impinge against the sides rather than directly against the door- 30 equipped front as is ordinarily done with the regular installation. The result is a more uniform circulation and distribution of air in the ash pit which, it is believed, accounts for fuel saving, more satisfactory and efficient combustion 35 in the fire box, and other results calculated to promote efficiency and to minimize fire hazards.

It is apparently unnecessary to attempt to theoretically trace the exact motion of the air, for the invention has been built upon experimental lines and has proved to be satisfactory 40 in insuring a more perfect combustion in the fire box and consequently a conservation of coal or other fuel utilized in the boiler.

It is thought that the description taken in connection with the drawings will enable a clear 45 understanding of the invention to be had. Therefore, a more lengthy description is thought unnecessary.

While the preferred embodiment of the invention has been shown and described, it is to be understood that minor changes coming within the 50 field of invention claimed may be resorted to if desired.

I claim:

1. As a component unit in a structural assemblage of the class described, a sheet of resilient metal bent upon itself between its ends to provide substantially duplicate converging baffle plates, bolt and nut means adjustably connecting the diverging end portions of said baffle plates together, said diverging end portions of the plates being provided with upper and lower outwardly and laterally directed flanges for air deflecting 10 and control purposes. 5

2. An attachment of the class described comprising a flanged coupling sleeve for use in association with a blower nozzle, a connecting pin mounted in said sleeve, a substantially V-shaped 15 baffle unit fashioned at one end for connection with said pin, said unit having its diverging end portions projecting beyond the flanged end of the sleeve, said diverging ends being provided with upper and lower laterally directed companion air deflector flanges, and means adjustably connecting the free diverging ends of said 20 diverging end portions. 25

3. In a draft equalizer of the class described, a sleeve adapted to be fitted telescopically over the nozzle of an air blower, said sleeve being provided at its boiler attaching end with an adapter and abutment flange, and an air equalizing unit, said unit comprising a substantially V-shaped member including complementary diverging baffle elements, the inner converging ends of said elements being located in said sleeve and attached to said connecting pin, the outer ends of said elements projecting beyond the flanged end of the sleeve and being of channeled cross-sectional 30 form, whereby to divide the incoming air stream as it passes on through and out of the flanged end of said sleeve and to shunt the air currents in diverging paths in the manner and for the purposes described. 35 40

4. In a device of the class described, an adapter sleeve designed to be fitted removably and telescopically on a delivery nozzle, and an air equalizing unit having one end fitted and fastened in the sleeve and the opposite end projecting beyond 45 the sleeve, the projecting end portion embodying outwardly diverging baffle elements and the upper and lower longitudinal edges of said elements being formed with laterally projecting deflector flanges. 50

WILLIAM BARENDTS.
